Sam'l H. Ransom, of Albany, N. Y.
Letters Patent No. 1093. Dated April 5. 1859.

The schedule referred to in these Letters Patent and making part of the same.

To whom it may concern:

Be it known that I, Samuel H. Ransom, of the City of Albany State of New York, have produced a new original ornamental design for the plates of a Cooking Stove, which Stove is named the "Wanderer," and I declare that the annexed delineations are full and accurate representations of the ornamented parts with their several ornaments, the back plate of the oven, and the left hand door of the oven, which are not shown being similar to their corresponding plates. — shown, and the right hand front door of the Stove being symmetrically similar to the left hand door shown.

What I claim as my production and desire to secure by Letters Patent is the combination and arrangement of ornamental figures and forms, represented in the accompanying drawings forming together the ornamental design for the plates of a Cooking Stove. —
